ABSTRACT

A watch having a crystal controlled watch movement mounted in a watch case is provided with a crystal oscillator circuit, internal manually operative oscillator circuit adjustment means located on the underside of the watch movement adjacent the bottom wall of the watch case, visual time display means, and manually operative internal display adjustment means also located on the underside of the watch movement adjacent the bottom wall of the watch case. The bottom wall of the watch case is provided with external manually operated means connected to the internal display adjustment means for changing the time displayed by the display means, and is also provided with removable access means for providing access to the internal oscillator circuit adjustment means for fine tuning the frequency of oscillation of said oscillator circuit.

CRYSTAL CONTROLLED WATCH

BACKGROUND OF THE INVENTION

1. Field of the Invention

This invention relates to crystal controlled electronic watches.

2. Prior Art

Crystal controlled electronic timepieces (for example, wrist watches) are well known in the art. A typical timepiece comprises a crystal controlled oscillator circuit for generating a high frequency oscillating signal, a divider circuit for dividing the high frequency signal into a lower frequency oscillating signal, visual time display means (for example, an array of seven-segment light emitting diodes or liquid crystal displays), and a replaceable battery for powering the electronic components. Manually operative oscillator circuit adjustment means are provided for fine tuning the frequency of oscillation of the oscillator circuit, and manually operative display adjustment means are provided for changing the time displayed by the time display means of the timepiece. In some timepieces, manually operative means are provided for energizing and/or illuminating the normally dark visual time display means whenever the user wishes to know the time. In the case of a wrist watch, these components are assembled together in a compact unit commonly referred to as the watch movement.

The watch movement is mounted in a protective and decorative watch case. The watch case normally has a generally tubular side wall, a transparent top wall secured to the upper peripheral edge of the side wall, and a bottom wall secured to the lower peripheral edge of the side wall. The watch movement is placed within the case with the time display means adjacent the transparent top wall. The case is then closed, usually by screwing the back wall into the side wall. The side wall is formed with a number of openings through which various knobs and/or push buttons extend which connect with the manually operative time display and other adjustment means of the watch movement so as to permit the time displayed by the display means to be correctly set and regulated. As noted, some watch movements are designed so that the visual time display means will be illuminated only when the wearer wishes to know the time. In these watches the side wall of the case must be provided with an additional manually operated push button in order to illuminate the time display means. The need to align the manually operative display adjustment means and other internal components of the watch movement with the various knobs and/or push buttons in the side wall of the watch case adds considerably to the difficulty and expense of assembling the watch.

The profusion of knobs and push buttons protruding from the side wall of a conventional crystal controlled electronic watch detracts from the esthetically pleasing appearance of the watch case and contributes to the possibility of accidental damage to these vulnerable parts. Moreover, although the watch movement is provided with internal manually operative oscillator circuit adjustment means, the watch can normally be fine turned for accuracy only by removing the movement from the watch case so as to provide access to the oscillator circuit adjustment means. This normally requires

return of the watch to the manufacturer at considerable inconvenience and expense to the user.

After an intensive investigation of shortcomings and problems of conventional crystal controlled electronic watch design, I have now devised a new watch configuration which eliminates the profusion of knobs and buttons from the sides of the watch case and also provides for fine tuning of the oscillator circuit without removing the movement from the case. The improved watch configuration provides for great ease in the assembly of the watch movement and watch case and adds to the esthetic appearance of the watch.

SUMMARY OF THE INVENTION

15 The general type of electronic watch to which the invention relates comprises a crystal controlled watch movement mounted in a watch case. The watch movement has a crystal controlled oscillator circuit, manually operative oscillator circuit adjustment means for 20 fine tuning the frequency of oscillation of the oscillator circuit, visual time display means, and manually operative internal display adjustment means for changing the time displayed by said display means. The watch case has a generally tubular side wall, a generally transparent top wall, a generally circular bottom wall, and exterior manually operated means mounted on the case and connected to the said internal display adjustment means. In accordance with the invention, the internal visual display adjustment means and the oscillator circuit adjustment means are located on the underside of the watch movement adjacent the bottom wall of the watch case. The watch case has a bottom wall that is provided with exterior manually operated means connected to the internal display adjustment means and it 30 is also provided with access means for providing access to the internal oscillator circuit adjustment means for fine tuning the frequency of oscillation of said oscillator circuit.

40 The top wall and side wall of the watch case are advantageously permanently secured together, the bottom wall being adapted to be releasably secured to the side wall adjacent to the lower peripheral thereof. The watch movement is preferably secured to the inner surface of the bottom wall to form a unitary subassembly that can be readily inserted in and secured to the open bottom of the side wall of the watch case. The positioning of the internal time display and oscillator frequency adjustment means on the underside of the watch movement permits ready alignment of the internal adjustment means with the exterior manually operated adjustment means mounted on the bottom wall of the watch case. In addition, the unitary subassembly of bottom wall and watch movement can readily be inserted in and secured to the side wall of the watch case without the need for troublesome alignment of the internal watch movement adjustment means with the various knobs and push buttons that extend through the side wall of conventional electronic watch cases. Other advantages of my improved watch configuration will become apparent from the following description thereof.

BRIEF DESCRIPTION OF THE DRAWING

65 The improved electronic watch configuration of the invention will be better understood from the following description in conjunction with the accompanying drawings of which:

FIG. 1 is a plan view of the top or face of a watch embodying the invention.

FIG. 2 is a plan view of the bottom or back of the watch of FIG. 1.

FIG. 3 is a sectional view along line 3—3 of FIG. 2 and

FIG. 4 is an exploded perspective view of the watch.

DESCRIPTION OF PREFERRED EMBODIMENT

The principal functional components of a crystal controlled electronic watch comprise a crystal oscillator circuit for generating a high frequency signal, a divider circuit for dividing the high frequency signal into a lower frequency signal, visual time display means for displaying the time of day in digital form, and a replaceable battery for providing electrical energy for the electronic components. Means are provided for manually adjusting the time displayed by the time display means, and means are advantageously provided for fine tuning the frequency of oscillation of the oscillator circuit. In some cases, manually operative means are provided for activating a special circuit that causes the normally dark visual display means to be illuminated whenever the user wishes to know the time.

The crystal controlled oscillator circuit typically employs a quartz crystal that generates an 8,640 kHz signal. The divider circuit divides or reduces the high frequency signal to, usually, 1 Hz. The visual time display means may comprise, for example, an array of seven-segment light emitting diodes or liquid crystal displays. Integrated circuits of the complementary-symmetrical metal-oxide-semiconductor (COSMOS) type are advantageously employed. These electronic components are assembled together in a compact unit referred to as the watch movement, and the watch movement is mounted in a protective and decorative watch case. All of the aforementioned electronic and structural components, and their assembly together in an attractive and functional unit, are well known in the art and do not comprise, in themselves, the present invention.

The present invention comprises a novel configuration or arrangement of the aforementioned components which greatly facilitates the assembly of the watch movement in the watch case and which provides for convenient adjustment of both the time display means and the frequency of oscillation of the oscillator circuit without removing the movement from the watch case. As shown in the drawings, the watch assembly comprises a crystal controlled electronic watch movement 11 mounted in a decorative and protective watch case 12. The electronic watch movement 11 is of essentially conventional design in that it includes a crystal oscillator circuit and a divider circuit (indicated generally by reference numeral 13), a visual time display means 14, manually operative oscillator circuit adjustment means 15 and manually operative visual display adjustment means 16. The watch case 12 comprises a transparent (or partially transparent) top wall 18, a generally tubular side wall 19 and a bottom wall 20. A replaceable battery 21 provides electrical energy for the electronic components of the watch movement. The battery 21 is placed in position through the battery hatch opening 22 formed in the bottom wall, the opening 22 being closed by the battery hatch closure plug 23 as shown in FIG. 3 of the drawings. The side wall 19

is provided with lugs 24 for attaching a watch strap to the watch case.

In accordance with the invention, the internal manually operative oscillator circuit adjustment means 15 for fine turning the frequency of oscillation of the crystal oscillator and the internal manually operative visual display adjustment means 16 for adjusting the time of day displayed by the visual display means 14 are located on the underside of the watch movement 11 adjacent the bottom wall 20 of the watch case 12. In the embodiment shown in the drawings the manually operative oscillator circuit adjustment means 15 is provided with a rotatable adjustment screw 26 by means of which the frequency of oscillation of the oscillator circuit may be tuned, and the internal manually operative visual display adjustment means 16 is provided with pressure actuated momentary contact switches which control the operation of the time display adjustment means in the manner hereinafter described.

Also in accordance with the invention, the bottom wall 20 of the watch case is provided with exterior manually operated means 28 and 29 which cooperate with the internal manually operative visual time display adjustment means 16 for adjusting the time of day displayed by the visual display means 14. In the embodiment shown in the drawings the exterior manually operated means 28 and 29 comprise a pair of push buttons (labeled "S1" and "S2" in FIG. 2) which are aligned and in contact with the pressure actuated contact switches of the time display adjustment means 16. Other types of exterior manually operated means can, of course, be employed provided they are adapted to be mounted on the bottom wall of the watch case. The bottom wall 20 is also provided with access means 30 for providing access to the internal manually operative means 15 for adjusting the frequency of oscillation of the crystal oscillator. In the embodiment shown in the drawings the access means 30 comprises a screw plug (labeled "A1" in FIG. 2) which when removed from the bottom wall 20 of the watch case provides access to the adjustment screw 26 of the oscillator circuit adjustment means 15.

The top wall 18 of the watch case 12 is firmly secured to the upper peripheral edge of the side wall 19 of the watch case. The top wall 18 may be completely transparent as in the case of a conventional watch crystal. In the embodiment shown in the drawings the top wall is provided with a transparent window 32 disposed directly over the visual display means 14 of the watch movement 11, the remainder of the top wall 18 being decorated with an opaque or partially opaque design which masks the other portions of the watch movement from view. The bottom wall 20 of the watch case is designed to be removably secured (for example, by a snap fit or by screen threads) to the lower peripheral edge of the side wall 19 of the watch case. In the embodiment shown in the drawing the bottom wall is provided with a vertically extending inner flange portion 34 which is designed to fit snugly within and in contact with the inner surface of the side wall 19 of the watch case. The bottom wall 20 is secured to the side wall 19 by the snug contact, preferably a press fit, between the inner flange portion 34 and the inner surface of the side wall 19. A gasket 35 is advantageously disposed between facing surfaces of the side wall 19 and the bottom wall 20 to provide a water resistant seal therebetween.

The watch movement 11 is firmly secured to the inner surface of the bottom wall 20 of the watch case before the bottom wall is secured to the side wall 19 of the watch case. In the embodiment shown in the drawing the watch movement 11 is secured to the bottom wall 20 by means of the screws 37 which are received in the threaded boss portions 38 on the inner surface of the bottom wall 20. Other means for securing the watch movement 11 to the inner surface of the bottom wall 20 may obviously be employed. When the watch movement 11 is secured to the bottom wall 20 the exterior manually operative means 28 and 29 are automatically aligned with the internal manually operative visual time display adjustment means 16, and the access means 30 is automatically aligned with the internal manually operative means 15 for adjusting the frequency of oscillation of the crystal oscillator. The watch is then assembled by inserting the watch movement into the open bottom of the side wall 19 of the watch case and by securing the bottom wall 20 to the side wall as hereinbefore described. This arrangement eliminates the difficulty previously encountered with aligning the internal adjustment means of the watch movement with the various push buttons and knobs extending through the side wall of conventional watch cases and thereby greatly facilitates the assembly of the watch.

When the watch is assembled as described the time displayed by the visual display means 14 is adjusted by appropriate manipulation of the exterior manually operated means 28 and 29 (push buttons "S1" and "S2"). The particular manipulative operations required to set the watch to the correct time will vary from one watch to another, depending on its internal circuitry. The sequence of manipulative steps employed in one watch embodying the invention are set forth in the following table.

TABLE I

Switch S1	Switch S2	Function After Switch Closure
Open	Open	Normal Operation.
Open	Closed	Hours advance at the rate of one per second as long as switch is closed.
Closed	Open	Sets S2 to minutes update mode.
Momentarily Open	Closed	Minutes advance at the rate of one per second. Minutes should be advanced at least 1 minute ahead of the actual time.
Open	Open	When S2 is released, the watch is in a hold mode (not running). Seconds are reset to 00 automatically.
Closed	Open	Watch starts running. S1 is momentarily closed when the watch being set is synchronized with an accurate time source.

The word "open" in the above table means that the switch involved is not being depressed, and the word "closed" means that the switch is being depressed.

The frequency of oscillation of the oscillator circuit is adjusted by removing the screw plug access means 30 to make accessible the adjustment screw 26 of the oscillator circuit adjustment means 15. Clockwise rotation of the screw 26 increases the frequency of oscillation while counterclockwise rotation of the screw decreases the frequency of oscillation of the oscillator circuit. Incident radiation from the quartz crystal oscillator can be interrogated by an electronic frequency counter with sufficient resolution to permit adjustment

of the watch to an accuracy of 0.00 seconds per day, and this can be accomplished by a jeweler in less than one minute without removing the watch movement from the watch case. This is in marked contrast to conventional watch configurations wherein the watch movement must be removed from the case in order to adjust the accuracy of the watch. When this adjustment is made with the watch movement outside the watch case, the frequency of oscillation of the oscillator circuit invariably changes when the movement is reinstalled in the watch case. This necessitates repeated removal, adjustment, reinstallation and testing for accuracy of the watch movement to obtain a required high degree of accuracy. The improved watch configuration of the present invention eliminates this tedious and time consuming procedure.

I claim:

1. In an electronic watch comprising a crystal controlled watch movement mounted in a watch case; said watch movement having a crystal controlled oscillator circuit, manually operative internal oscillator circuit adjustment means for fine tuning the frequency of oscillation of the oscillator circuit, visual time display means, and manually operative internal display adjustment means for changing the time displayed by said display means; said watch case having a generally tubular side wall, a generally transparent top wall, a generally circular bottom wall, and exterior manually operated means mounted on the case and connected to said internal display adjustment means; the improvement which comprises:

internal display adjustment means located on the underside of the watch movement adjacent the bottom wall of the watch case, exterior manually operated means mounted on the bottom wall of the watch case and connected to the internal display adjustment means for changing the time displayed by said display means.

internal oscillator circuit adjustment means located on the underside of the watch movement adjacent the bottom wall of the watch case, and access means mounted on the bottom wall of the watch case for providing access to the internal oscillator circuit adjustment means for fine tuning the frequency of oscillation of said oscillator circuit.

2. The watch according to claim 1 in which the top wall is permanently secured to the side wall of the watch case adjacent the upper peripheral edge thereof, in which the bottom wall is adapted to be releasably secured to the side wall adjacent the lower peripheral edge thereof, and in which the watch movement is secured to the inner surface of the bottom wall of the watch case prior to securing the bottom wall to the side wall of the watch case.

3. The watch according to claim 2 in which the bottom wall is provided with a vertically extending inner flange portion, said inner flange portion being adapted to fit snugly within and in contact with the inner surface of the side wall of the watch case, said bottom wall being secured to said side wall by the snug contact fit of said inner flange portion with the inner surface of said side wall.

4. The watch according to claim 3 in which a gasket is disposed between facing surfaces of the side wall and the bottom wall to provide a water resistant seal therebetween.

5. The watch according to claim 1 in which the access means on the bottom wall of the watch case comprises a removable screw plug.
